VACUUM CLEANER ATTACHMENT

Bernard S. Jablon, New York, N. Y.

Application May 12, 1947, Serial No. 747,537

5 Claims. (Cl. 183—51)

1

This invention relates to a vacuum cleaner and particularly to an attachment for a vacuum cleaner which will reduce the back pressure caused by the resistance of the air bag, and yet cause the dirt carried by the moving air stream to separate from the air before being exhausted to the room atmosphere, and thus by diminishing the back resistance of the air bag increase the force of the suction to pick up dirt.

One of the objects of the invention is the provision of a vacuum cleaner with an attachable exhaust outlet having means for separating the dirt from the air, so arranged that more rapid discharge of the air stream is permitted.

Another object of the invention is the provision of a construction which will accomplish this object, which can be readily secured to the upper end of the air bag of a vacuum cleaner, and which will permit of ready cleaning of the filtering means enclosed by it.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevation showing a vacuum cleaner having an air bag equipped with the improved exhaust device.

Fig. 2 is a longitudinal sectional view, taken on line 2—2 of Fig. 1, looking in the direction of the arrows.

Fig. 3 is a top end view of the attachment, showing the exhaust openings thereof.

Fig. 4 is a cross sectional view, taken on line 4—4 of Fig. 2, looking in the direction of the arrows.

Referring to the drawings, which illustrate the practical embodiment of the invention, 10 designates a motor driven vacuum cleaner having an intake base 11, and a discharge hood 12, to which the lower end of the air bag 13 is secured as by the coupling 14. The vacuum cleaner is equipped with the usual control handle 15, and the upper end of the bag 13 is supported from this handle by means of the hanger 16. These parts are old and well known.

In carrying out the present invention, the upper end of the bag is formed with an open hole, in which an inner metal tube 17 is inserted. This tube is formed or provided with an internal end flange 18 on its upper end, which is formed with a central bearing 19, and with circular exhaust

2

holes 20, disposed in a circular row around the bearing 19, and equally spaced from each other.

The upper tubular end 21 of the air bag 13 is snugly fitted around the tube 17, and an outer metal sleeve 22 is then forced over the tubular end 21 and secured by the engaging screw threads 23 to the tube 17, so as to clamp the bag end thereto. The upper end of the sleeve 22 is formed with an internal flange 24, to engage the flange 18 of the tube 17.

In order to lock the tubular upper end of the air bag to the wall of the metal sleeve 22, this sleeve is formed with an internal groove 25, into which the fabric of the air bag is forced by means of the internal spring ring 26.

Within the inner tube 17 a series of spaced discs 27, of sponge material, or of filter material, are arranged. These discs are formed with a plurality of transverse discharge openings 28, and the openings of one disc are offset with reference to the openings of the adjacent discs. Below these discs a supply of filter material 29, such as fibre glass, is arranged. The filter material and the discs of sponge material are held against the upper internal end flange 18 by means of the inner disc 30, which engages a seat 31 formed in the inner end of the inner tube 17. A rod 32 extends through the inner and lower disc 30, through the filter material 29 and the discs 27 of sponge material, and through the end wall 18. The lower end of this rod 32 is provided with a head 32a which bears against the inner and lower disc 30 and which extends through the bearing 19 to receive the clamping nut 33, the turning of which will clamp the lower disc 30 against the inner end of the sleeve 17, and thereby clamp the discs 27 against the end wall 18, and the filter material against the disc 27. The inner and lower disc 30 is formed with open discharge ports or holes 30a.

When the vacuum cleaner 10 is operated in the usual manner, the air stream which is discharged into the bag will flow in part through the porous wall of the bag, and in part through the attachment, passing through the openings of the lower disc 30, through the filtering material 29 and the perforated discs 27, and thence through the holes of the end wall 18 to the room atmosphere.

The total resistance offered by the attachment is less than that offered by the wall of the air bag, so that the back pressure developed by the resistance of the air bag to the exhaust flow of the air stream is reduced.

The air discharging through the filtering material and the sponge discs releases dirt which

would pass through the wall of the air bag, because of the baffle action set up by the staggered arrangement of the openings 28 of the sponge discs.

By detaching the sleeve 22 the sponge discs and filtering material may be cleaned or replaced. Any disinfecting fluid may be sprayed or sprinkled in the filtering material, so that the discharging air stream will cause the room in which the vacuum cleaner is operated to be disinfected.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. In combination with a vacuum cleaner bag having a discharge opening at the top end thereof, a filter mounted in the discharge opening, comprising an inner sleeve having one end inserted into the discharge opening and formed at its inner end with a circular seat and having its outer end closed by a wall formed with a central bearing and a plurality of exhaust holes arranged in a circle about said central bearing, means securing the material of the bag defining the discharge opening about the periphery of said sleeve, a plurality of discs held spaced from one another positioned in said inner sleeve, the outermost of said discs being in facial contact with the inner face of said wall, said discs having offset openings communicating with the discharge openings of said wall and aligned holes aligned with said central bearing, filter material positioned in said sleeve in contact with the innermost of said spaced discs, an inner disc engaging said circular seat closing the open end of said sleeve and formed with a central hole aligned with the aligned holes of said spaced discs and a plurality of openings leading from the bag into said sleeve formed in said inner disc about said central hole, and means engaged through said central hole of said inner disc, said filter material, said aligned holes of said spaced discs, and said central bearing securing said inner disc in position on said circular seat.

2. In combination with a vacuum cleaner bag having a discharge opening at the top end thereof, a filter mounted in the discharge opening, comprising an inner sleeve having one end inserted into the discharge opening and formed at its inner end with a circular seat and having its outer end closed by a wall formed with a central bearing and a plurality of exhaust holes arranged in a circle about said central bearing, means securing the material of the bag defining the discharge opening about the periphery of said sleeve, a plurality of discs held spaced from one another positioned in said inner sleeve, the outermost of said discs being in facial contact with the inner face of said wall, said discs having offset openings communicating with the discharge openings of said wall and aligned holes aligned with said central bearing, filter material positioned in said sleeve in contact with the innermost of said spaced discs, an inner disc engaging said circular seat closing the open end of said sleeve and formed with a central hole aligned with the aligned holes of said spaced discs and a plurality of openings leading from the bag into said sleeve formed in said inner disc about said central hole, and means engaged through said central hole of said inner disc, said filter material, said aligned holes of said spaced discs, and said central bearing securing said inner disc in position on said circular seat.

5 the bag into said sleeve formed in said inner disc about said central hole, and means engaged through said central hole of said inner disc, said filter material, said aligned holes of said spaced discs, and said central bearing securing said inner disc in position on said circular seat, said securing means comprising an outer metal sleeve threadedly engaged about said inner sleeve and having one end overlapping the material of the bag defining the discharge opening, an annular groove formed on the end of said outer sleeve which overlaps the material of the bag, and a spring ring within the bag holding a portion of the material defining the discharge opening pressed into said annular groove.

sleeve in contact with the innermost of said spaced discs, an inner disc engaging said circular seat closing the open end of said sleeve and formed with a central hole aligned with the aligned holes of said spaced discs and a plurality of openings leading from the bag into said sleeve formed in said inner disc about said central hole, and means engaged through said central hole of said inner disc, said filter material, said aligned holes of said spaced discs, and said central bearing securing said inner disc in position on said circular seat, said latter-mentioned means, comprising a rod having a threaded end passed through said central hole of said inner disc, said filter material, said aligned holes of said spaced discs and said central bearing, and a nut engaged on the threaded end of said rod and abutting said wall.

5. In combination with a vacuum cleaner bag having a discharge opening at the top end thereof, a filter mounted in the discharge opening, comprising an inner sleeve having one end inserted into the discharge opening and formed at its inner end with a circular seat and having its outer end closed by a wall formed with a central bearing and a plurality of exhaust holes arranged in a circle about said central bearing, means securing the material of the bag defining the discharge opening about the periphery of said sleeve, a plurality of discs held spaced from one another positioned in said inner sleeve, the outermost of said discs being in facial contact with the inner face of said wall, said discs having offset openings communicating with the discharge openings of said wall and aligned holes aligned with said central bearing, filter material positioned in said sleeve in contact with the innermost of said spaced discs,

an inner disc engaging said circular seat closing the open end of said sleeve and formed with a central hole aligned with the aligned holes of said spaced discs and a plurality of openings leading from the bag into said sleeve formed in said inner disc about said central hole, and means engaged through said central hole of said inner disc, said filter material, said aligned holes of said spaced discs, and said central bearing securing said inner disc in position on said circular seat, said latter-mentioned means, comprising a rod having a threaded end passed through said central hole of said inner disc, said filter material, said aligned holes of said spaced discs and said central bearing, and a nut engaged on the threaded end of said rod and abutting said wall, and an enlarged head formed on the end of said rod opposed to the threaded end thereof and abutting the adjacent face of said inner disc.

20 BERNARD S. JABLON.
